UNITED STATES PATENT OFFICE.

WILLIAM M. SCOTT, OF TREDYFFRIN TOWNSHIP, CHESTER COUNTY, PENNSYLVANIA.

SWITCH-HOUSING STRUCTURE.

Application filed August 30, 1921. Serial No. 496,816.

To all whom it may concern:

Be it known that I, WILLIAM M. SCOTT, a citizen of the United States, residing in Tredyffrin Township, in the county of Chester and State of Pennsylvania, have invented a new and useful Switch-Housing Structure, of which the following is a specification.

My invention relates to structure for 10 mounting and housing electric switches, automatic circuit breakers, and the like.

In accordance with my invention, there is provided a supporting housing by which is supported, in hinged or pivotal relation thereto, a base carrying switch or automatic circuit breaking mechanism, with a second housing enclosing the switching or circuit breaking mechanism, the latter preferably provided with a hinged wall or door upon 20 which is mounted movable structure for actuating or controlling the switching or circuit breaking mechanism.

My invention resides in the features of construction and combination hereinafter 25 described and claimed.

For an illustration of some of the various forms my invention may take, reference is to be had to the accompanying drawings, in which:

30 Fig. 1 is a side elevational view of apparatus embodying my invention.

Fig. 2 is a front elevational view of the same.

Fig. 3 is a fragmentary view illustrating 35 detachable hinge structure of the apparatus shown in Fig. 1.

Fig. 4 is an elevational view of a modified form of my apparatus.

Fig. 5 is a front elevational view of the 40 same.

Fig. 6 is a bottom view of the apparatus shown in Fig. 4.

Fig. 7 is a side view of a further form of my apparatus.

45 Referring to Figs. 1, 2 and 3, A is a housing or box of any suitable material, preferably sheet or cast metal, which, in the example illustrated, serves as a supporting housing, and is itself preferably secured to any suitable support, as a wall, pillar or the like, by any suitable attaching means, as screws 1, 1. Communicating with the interior of the housing A is a pipe or conduit 2 through which extend the supply circuit

conductors 3, which extend into the interior 55 of the housing A and connect with terminals 4 adapted to be connected to the herein-after described circuit breaker studs. A second conduit 5 communicates with the interior of the housing A and through it 60 extend the consumption circuit conductors 6, which extend into the housing A and connect with terminals 7 adapted for connection to the circuit breaker studs hereinafter referred to.

65 8 is a base, preferably of insulating material, such as slate, upon the front face of which is mounted switching mechanism, circuit breaker mechanism, or the like. In the example illustrated, and preferably, 70 there is employed automatic circuit breaker mechanism, which in the example illustrated comprises two breaker or switching mechanisms, constituting so-called "double arm" circuit breaker mechanism such, for example, 75 as shown in Letters Patent No. 1,389,996 or No. 1,480,306. In this connection it shall be understood that my invention is not limited in these respects, since the number of poles or arms of the circuit breaker or switching mechanism may be anything suitable or desirable.

80 These breaker arms are indicated at B and C, Fig. 2, the breaker mechanism B being shown in Fig. 1 in side elevation.

85 Each breaker arm comprises an upper main terminal 9 carried by the base 8 and having a stud 10 extending through the base and projecting into the housing A, the afore-said terminal 4 being secured upon the stud 90 10 and therefore electrically connecting therewith. Co-acting with the terminal 9 is the movable contact member 11 co-acting with the lower terminal 12 disposed below the terminal 9 and with which connects one 95 terminal of the electromagnet coil 13, whose other terminal connects with the stud 14 extending through the base 8 and projecting into the housing A, where the terminal 7 is secured upon the stud 14 and electrically 100 connected therewith. The movable contact member 11 is operated by toggle mechanism 15 having the member 16 through which the toggle is actuated. The breaker is latched or restrained in normal position, as well understood in the circuit breaker art, the restraining means or latch being controlled by 105 the armature 17 of the tripping magnet 13,

Enclosing the switch or circuit breaker mechanism is the housing D, preferably of sheet or cast metal, secured to the base 8, and in the example illustrated forming therewith a unit pivoted or hinged upon the housing A by any suitable means. In the example illustrated, the housing D has secured thereto a pair of hinge hooks 18 extending through slots or openings in plates 19 secured to the housing A. By this arrangement the base 8 and housing D, and parts carried thereby, may be swung upon the supporting housing A, Fig. 1 indicating the base 8 and housing D swung away from the housing A. When the base 8 is vertical it closes the housing A, and forms in effect a wall common to both housings A and D. The base and the parts carried thereby may be secured in the last mentioned position, as by screws 20 extending through the base 8 and threading into suitable clips 21 secured within the housing A.

Hinged or pivoted to the housing D at 22 is the door or movable wall E, which is adapted to be retained in closed position by the spring catch 23 secured upon the interior of the housing D and extending through an aperture 24 in the door E.

Secured upon the door E and disposed upon the inside thereof is the bracket member 25, in which is carried the rod or shaft 26 upon which is secured the rotatable member 27, which is operable in opposite directions by the handle 28 for engaging the aforesaid members 16, 16 in succession for resetting the breaker arms B and C in succession. The shaft 26 is also movable longitudinally inward, by pressure upon the button 29, to actuate the member 30 pivoted upon the bracket 25 and adapted to engage the restraining means of the circuit breaker, whereby the same may be manually tripped. Operating and tripping mechanism of the character described is illustrated in my Letters Patent No. 1,515,759, it being understood, however, that my invention is not limited in this respect.

While in Fig. 1 the base 8 and housing D are pivoted or hinged on a horizontal axis upon the housing A, it will be understood that the hinge structure may be such that the base 8 swings upon hinges whose pivotal axes are vertical.

Such an arrangement is indicated in Figs. 4, 5 and 6, wherein the housing D is hinged to the housing A at 31. While the door or movable wall E may be pivoted to the housing D on horizontal hinges as in Fig. 1, in the example illustrated it is pivoted to the housing D on the vertical hinges 32.

In Fig. 7, as in my Letters Patent No. 1,389,996, the housing D is secured to the base 8, and the base 8 is secured to the supporting housing A. There are secured to the base 8 the hook hinge members 33 received in

suitable apertures or slots in the bottom of the housing D, which is placed upon the hook hinges 33 while in an inclined position, indicated in dotted lines, and then moved to final position against the base 8, as shown in full lines, and there secured by the screw 34 threaded into the sleeve 35 secured to the post 36, which is in turn secured upon the base 8.

What I claim is:

1. The combination with a fixed housing, of a base member hinged thereon, switching mechanism comprising co-operating relatively fixed and movable contacts carried by said base member, connecting means extending from said switching mechanism through said base member into said housing, and conductors extending from the exterior into said housing and connecting with said connecting means.

2. The combination with a supporting housing, of means for securing the same to a support, a base of insulating material, switching mechanism comprising co-operating relatively fixed and movable contacts carried upon one side of said base, means hinging said base to said supporting housing for supporting said base upon said housing, connecting means extending from said switching mechanism through said base into said housing, and conductors extending from the exterior into said housing and connecting with said connecting means.

3. The combination with a housing, of a base of insulating material, means detachably hinging said base upon said housing, switching mechanism comprising co-operating relatively fixed and movable contacts carried by said base, and connecting means extending from said switching mechanism through said base into said housing.

4. The combination with a base, of a housing, and means detachably securing said base and housing to each other comprising hook members secured in fixed relation with respect to one of them and detachably engaging the other, and switching mechanism comprising co-operating relatively fixed and movable contacts carried by said base.

5. The combination with a plurality of housings, of a base of insulating material forming a wall common to them, switching mechanism comprising co-operating relatively fixed and movable contacts mounted on said base, and means for detachably connecting one of said housings with said base, comprising hook structure.

6. The combination with a housing, of a base member hinged thereon, switching mechanism comprising co-operating relatively fixed and movable contacts carried by said base member, connecting means extending from said switching mechanism through said base member into said housing, conductors extending from the exterior into

- 5 said housing and connecting with said connecting means, and a second housing enclosing said switching mechanism and forming a unit with said base.

5 7. The combination with a housing, of a base member hinged thereon, switching mechanism comprising co-operating relatively fixed and movable contacts carried by said base member, connecting means extending 10 from said switching mechanism through said base member into said housing, conductors extending from the exterior into said housing and connecting with said connecting means, a second housing enclosing 15 said switching mechanism and forming a unit with said base, and controlling means detached from said switching mechanism carried within a wall of said second housing and operable from the exterior thereof.

20 8. The combination with a housing, of a base member hinged thereon, switching mechanism comprising co-operating relatively fixed and movable contacts carried by said base member, connecting means extending 25 from said switching mechanism through said base member into said housing, conductors extending from the exterior into said housing and connecting with said connecting means, a second housing enclosing 30 said switching mechanism, and a pivoted door for said second housing.

9. The combination with a housing, of a base member hinged thereon, switching mechanism comprising co-operating relatively fixed and movable contacts carried by said base member, connecting means extending 35 from said switching mechanism through said base member into said housing, conductors extending from the exterior into said housing and connecting with said connecting means, a second housing enclosing 40 said switching mechanism, a pivoted door for said second housing, and switch controlling means carried by said door and operable from the exterior for controlling 45 said switching mechanism.

10. The combination with a plurality of 50 housings, of a base of insulating material forming a wall common thereto and movable as a unit with one of said housings, said base, and said one of said housings hinged to another of said housings, switching mechanism comprising co-operating relatively fixed and movable contacts within 55 said one of said housings carried upon said base, connecting means extending from said switching mechanism through said base into said other of said housings, and conductors extending from the exterior into said other 60 of said housings and connecting with said connecting means.

65 11. The combination with a housing, of a base member carried thereby, switching mechanism comprising co-operating relatively fixed and movable contacts carried by

5 said base member, connecting means extending from said switching mechanism through said base member into said housing, and a second housing enclosing said switching mechanism hinged to said first named 10 housing.

12. The combination with a housing, of a base member carried thereby, switching mechanism comprising co-operating relatively fixed and movable contacts carried by said base member, connecting means extending from said switching mechanism through said base member into said housing, a second housing enclosing said switching mechanism hinged to said first named housing, means 15 for securing said base member to said first named housing, and means securing said second housing to said base member.

13. The combination with a housing, of a base member carried thereby and forming a 20 wall thereof, switching mechanism comprising co-operating relatively fixed and movable contacts carried by said base member, connecting means extending from said switching mechanism through said base 25 member into said housing and a second housing enclosing said switching mechanism and pivoted to said first named housing at an edge thereof adjacent said base 30 member.

14. The combination with a housing, of a base member, switching mechanism comprising co-operating relatively fixed and movable contacts carried by said base member, connecting means extending from said switching mechanism through said base 35 member into said housing, a second housing enclosing said switching mechanism and attached to said base to form a unit therewith, and means pivoting said unit to said 40 first named housing.

15. The combination with a housing, of a base member, switching mechanism comprising co-operating relatively fixed and movable contacts carried by said base member, connecting means extending from said switching mechanism through said base 45 member into said housing, a second housing enclosing said switching mechanism and attached to said base to form a unit therewith, means pivoting said unit to said first named housing, said second housing having a pivoted wall, and control mechanism for said switching mechanism carried by said wall 50 in detached relation to said switching mechanism.

16. The combination with a housing, of a base member, switching mechanism comprising co-operating relatively fixed and movable contacts carried by said base member, connecting means extending from said switching mechanism through said base 55 member into said housing, a second housing enclosing said switching mechanism and attached to said base to form a unit therewith,

means pivoting said unit to said first named housing, and means for securing said unit to said first named housing.

17. The combination with a support, of 5 conductors mounted adjacent thereto, a switch box pivotally connected to said support, switching mechanism comprising co-operating relatively fixed and movable contacts mounted in and movable with said box, 10 and conductors extending from said mechanism and adapted to be connected with said first named conductors.

18. The combination with a support, of 15 conductors mounted adjacent thereto, a base pivotally mounted on said support, switching mechanism comprising co-operating relatively fixed and movable contacts carried by said base and having terminals adapted to be connected to said conductors, 20 a housing for said mechanism movable therewith and with said base, and a switch-actuating member carried by said housing on its exterior.

19. The combination with a fixed housing, 25 of a base member pivoted thereon, an automatic circuit breaker comprising co-operating relatively movable contact structures, means for restraining them in normal position, and automatic tripping mechanism, 30 carried by and movable as a unit with said base member, connectors extending from said circuit breaker through said base member into said housing, and conductors extending from the exterior into said housing 35 and detachably connecting with said connectors.

20. The combination with a fixed housing,

of a base member pivoted thereon, an automatic circuit breaker comprising co-operating relatively movable contact structures, 40 means for restraining them in normal position, and automatic tripping mechanism, carried by and movable as a unit with said base member, connectors extending from said circuit breaker through said base member into said housing, conductors extending from the exterior into said housing and detachably connecting with said connectors, and a second housing enclosing said circuit breaker and movable with said base member. 50

21. The combination with a fixed housing, of a base member pivoted thereon, an automatic circuit breaker comprising co-operating relatively movable contact structures, 55 means for restraining them in normal position, and automatic tripping mechanism, carried by and movable as a unit with said base member, connectors extending from said circuit breaker through said base member into said housing, conductors extending from the exterior into said housing and detachably connecting with said connectors, a second housing enclosing said circuit breaker and movable with said base member, said second housing having a movable wall, and 60 means operable from the exterior of said second housing carried by said movable wall in detached relation to said movable contact structure for re-setting said circuit breaker. 70

In testimony whereof I have hereunto affixed my signature this 29th day of August, 1921.

WILLIAM M. SCOTT.
